CORPSE PRESERVER

Herbert I. Berger, St. Louis, Mo.

Application July 27, 1940, Serial No. 347,931

4 Claims.

(Cl. 27—23)

This invention relates to a certain new and useful improvement in structures that may be descriptively designated as corpse preservers.

The invention has for its objects the provision of a structure of the type and for the purpose mentioned which may be cheaply, readily, and inexpensively constructed, which may be conveniently disposed embracingly about the body, and which is efficient in the performance of its stated functions.

And with the above and other objects in view, my invention resides in the novel features of form, construction, arrangement, and combination of parts presently described and pointed out in the claims.

In the accompanying drawings (two sheets)—

Figure 1 is a perspective view of a corpse-preserving structure embodying my invention in preferred form;

20 Figure 2 is a longitudinal sectional view of the structure on approximately line 2—2, Figure 1;

Figure 3 is a transverse sectional view of the structure on approximately line 3—3, Figure 1;

25 Figure 4 is a reduced perspective view of a slightly modified structure embodying my invention;

Figure 5 is a transverse sectional view taken approximately on the line 5—5, Figure 4;

Figure 6 is a reduced perspective view of 30 another slightly modified structure embodying my invention;

Figure 7 is a transverse sectional view taken approximately on the line 7—7, Figure 6;

Figures 8 and 9 are plan and side elevational 35 views, respectively, of a telescopically collapsible structure embodying my invention, the structure being shown in fully extended condition for use;

Figure 10 is a plan view of the structure of Figure 8 in collapsed condition;

40 Figure 11 is a transverse sectional view taken approximately on the line 11—11, Figure 8;

Figure 12 is a plan view of another slightly modified type of knock-down structure embodying my invention; and

45 Figure 13 shows the structure of Figure 12 in knocked-down position for convenient portability.

Referring now more in detail and by reference characters to the accompanying drawings, which 50 illustrate practical embodiments of my invention, 1, 1, designate opposite parallel side walls, and 2, 2, designate opposite parallel end walls, all integrally or otherwise joined together in the formation of an oblong rectangular open-bottom 55 shell, as shown, and of suitable dimensions for

disposition to rest at the lower margin of said walls upon a table or the like and enclosingly or embracingly about a corpse or body A.

For appearance and strength, said walls 1, 2, are preferably beaded, as at a, along their upper and lower margins, and transversely spanning the chamber of the shell in longitudinally spaced relation and welded or otherwise preferably permanently fixed at their respective opposite ends to and upon the inner face of the opposite side walls 10 1, 1, are lengthwise arched shelves or supports 3 for a refrigerant in the form preferably of carbon dioxide or so-called "dry ice," as at 4. Each shelf 3 is formed along its opposite longitudinal margins with upstanding lateral ice-retaining flanges 15 or walls, as at b, and at and adjacent its opposite ends is formed with a multiplicity of apertures or perforations, as at 6, for passage of vapors from ice 4 downwardly into the chamber of the shell for preservation of the embraced body A. 20

Preferably a top wall in the form of a lid 7 is hingedly attached, as at 8, to a side wall 1 for swingably covering and concealing the several shelves 3, the lid 7 being preferably provided with a window or the like, as at 9, for exposing to 25 vision the face of the embraced body A, substantially as shown.

As will be evident, the structure may be readily and easily disposed over and about the body A and is exceedingly efficient in the accomplishment of its intended functions. 30

The structure may be constructed of sheet metal or of any suitable plastic or of any other suitable sufficiently rigid material for possible repeated use or may be constructed of any suitable 35 relatively stiff and inexpensive cardboard or the like that may economically be discarded following a single or individual use.

Further, if desired, the several walls 1^a, 2^a, of the shell may be of insulated type, as shown in 40 Figure 5, and the refrigerant supporting shelves may be in the form of perforated strips 3^a suitably so angularly fixed to the side and end walls 1^a, 2^a, to extend in transversely spaced relation longitudinally along the side walls 1^a, as best 45 seen in Figures 4 and 5.

Again, if desired, the shell may be of so-called knock-down or collapsible type for ready portability and to such end may include companion side wall sections 1^b and end wall sections 2^b each 50 formed with co-operable ears, as at 10, for accommodating either permanent or removable pintles 11, the side wall sections 1^b being suitably provided upon their inner face with pockets 12 for detachably receiving the correspondingly 55

flanged ends 13 of refrigerant supporting shelves 3^b, all as best seen in Figures 6 and 7.

Or the structure may have a somewhat so-called wedge-shape contour, as shown in Figure 12, and comprise companion U-shape members B, B, best seen in Figure 13, each provided or formed at the free end of its legs with ears, as at 10^a, for accommodating removable pintles 11^a for detachably securing the members B, B, in structure formation.

Or, if desired, the structure may likewise comprise opposed U-shape members C, C', as illustrated in Figures 8 and 9, the member C' being sized to fit at its legs within the companion member C and having headed studs or the like 14 working in longitudinal slots 15 in the side walls 1^c of the member C, as best seen in Figure 9, for facilitating telescopic movement of the one member C' relatively to its companion member C.

In both structures of Figures 8 and 12, the several shelves 3^c are each preferably formed at its opposite ends with suitably extended hook members 16 for connection with the opposite side walls of the structure, as best seen in Figures 11 and 12.

Thus the structure may be readily foldably or detachably collapsed for ease of portability and for convenient erection at the location selected for temporarily preserving the body A for burial, the several shelves 3^b and 3^c being quickly detached from the side walls of the particular structure and compactly assembled with the shell-forming members during portability.

It is to be understood that other modifications and changes in the form, construction, arrangement, and combination of the several parts of the structure may be made and substituted for those herein shown and described without departing from the nature and principle of my invention.

Having thus described my invention, what I

claim and desire to secure by Letters Patent is—

1. A portable corpse preserver including a plurality of companion members adapted for co-operation in the formation of an open-ended collapsible shell shaped for normal disposition about a body, and a plurality of refrigerant-supporting shelves disposed transversely, and detachably engaged with the side walls, of the shell in a longitudinally spaced series. 5

2. A corpse preserver including a pair of detachably joined U-shaped members providing when joined and extended an open-bottom shell shaped for refrigerant-supporting disposition about a body. 10

3. A corpse cooler comprising a pair of U-shaped wall-forming members provided at their transverse margins respectively with releasable interlocking means for forming, when connected together, a four-sided open-ended wall enclosure, and a plurality of foraminous shelf members sized 15 for extending transversely across said enclosure and provided at their opposite ends with means 20 for removable engagement with the U-shaped members.

4. A collapsible corpse preserver comprising a 25 pair of similar normally U-shaped members each comprising a pair of longitudinal sections and a transverse end section hingedly connecting the longitudinal sections, said longitudinal sections further being provided at their opposite transverse margins with releasably connectable interlocking means for joining the U-shaped members together in endwise connected relation in the formation of a four-sided wall-like enclosure, and shelf means removably engageable with the U-shaped members when in enclosure-forming relation and adapted to extend transversely across said enclosure. 30
